United States Patent Office

Des. 179,031
Patented Oct. 23, 1956

179,031

THREE-BOWL SINK

Alfred Browning Parker, Miami, Fla., assignor to
Elkay Manufacturing Company

Application February 3, 1955, Serial No. 34,354

Term of patent 14 years

(Cl. D4—2)

Fig. 2

Fig. 3

Fig. 4

Fig. 1 is a perspective view of a three-bowl sink showing my new design;

Fig. 2 is a top plan view thereof;

Fig. 3 is an elevational view of the front thereof; and

Fig. 4 is an end elevational view thereof.

The dominant feature of my design resides in the full line portion of the drawings.

I claim:

The ornamental design for a three-bowl sink, as shown and described.
